G. HAVELL.

MANUFACTURE OF KNIFE BLADES AND BOLSTERS.

No. 373,527.

Patented Nov. 22, 1887.

Fig. 2. Fig. 1. Fig. 4. Fig. 3.

UNITED STATES PATENT OFFICE.

GEORGE HAVELL, OF NEWARK, NEW JERSEY.

MANUFACTURE OF KNIFE BLADES AND BOLSTERS.

SPECIFICATION forming part of Letters Patent No. 373,527, dated November 22, 1887.

Application filed August 1, 1887. Serial No. 215,783. (No model.)

To all whom it may concern:

Be it known that I, GEORGE HAVELL, a citizen of the United States, residing at Newark, Essex county, New Jersey, have invented certain new and useful Improvements in Knife Blades and Bolsters, fully described and represented in the following specification and the accompanying drawings, forming a part of the same.

The object of this invention is to provide a sheet-metal knife-blade with a strong tang, and with a solid bolster fitted tightly upon the tang and shank of the blade.

To form a strong tang by which a sheet-metal blade may be rigidly secured in the handle, I cut the tang in one piece with the blade, but wide enough to swage upon the edges, so as to form it into a rounded bar of greater thickness than the blade. A bolster formed to slip over such tang would not then fit closely against the shank or butt of the blade, and to secure such close contact at the central point, where the hole through the bolster is enlarged to pass over the tang, I compress the entire bolster upon the tang and butt of the blade, and thus secure the close fit desired.

To fit the button-shank of the blade to the bolster, I form the butt adjacent to the tang with a convex outline, and form a concave recess in the upper end of the bolster, adapted to fit the thickness of the blade at that point.

The invention will be understood by reference to the annexed drawings, in which Figure 1 is a side view of the finished knife blade and bolster, with the latter in section. Fig. 2 is an edge view of the same with the bolster in section. Fig. 3 is an edge view of the blade with the bolster in section, shown ready for compression upon the tang and bed of the blade. Fig. 4 is a side view of the knife and bolster as completed. Fig. 5 is a longitudinal section of the bolster shown in Fig. 2. Fig. 6 is a similar section of the bolster shown in Fig. 1. Fig. 7 is a plan of the bolster shown in Figs. 2 and 5, and Fig. 8 is a plan of the bolster shown in Figs. 3 and 6. Fig. 9 is a side view of the blank for the tang attached to the butt of the blade. Fig. 10 is a diagram showing the dies operating upon the edges of the blank to form a round tang, and Fig. 11 a section of the dies to compress the bolster.

a is the knife-blade; *a'*, the blank for the tang; *b*, the finished tang; *c*, the convexities at the butt of the blade; *d*, the notch in the top of the bolster formed to receive the same, and *e* the hole formed longitudinally through the center of the bolster and intersecting such groove to permit the introduction of the tang.

In the manufacture of my improved knife I cut from suitable sheet metal a blank adapted to form the blade and tang, the part intended for the latter being made wider than the proposed tang, as shown at *a'* in Fig. 9, and then compressed upon its edges, as in the dies *g*, (shown in Fig. 10,) so as to make it narrower and thicker and impart to it a prismatic form, as round or square.

Heretofore the sheet-metal blades for case-knives have been secured in handles by forming a tang-plate as wide as the handle and riveting the latter in two parts upon the opposite side of such plate. By my invention I form a strong rigid tang of the sheet metal, but of such form as to be inserted wholly within the handle, like the tangs of forged blades, and thus produce a more valuable and attractive article for sale. When the tang is inserted through the bolster with the butt of the blade resting in the handle *d*, the hole *e* is exposed at the upper end of the bolster above the corners *b'* of the tang, forming cavities *e'* at each side of the blade, which would not only mar the appearance of the bolster, but permit the access of water to the interior of the handle to which the tang was fitted. To close such cavities I apply suitable dies, *g'*, to the bolster, as shown in Fig. 11, and compress it closely against the knife-blade over the upper shoulder of the tang, as shown in Fig. 2, and thus form a close permanent joint between the bolster and butt of the blade, as illustrated in Fig. 4.

The appearance of the bolster before compression is shown in Figs. 6 and 8, and after the compression in Figs. 5 and 7, the sides of the hole *e* being forced inward to close contact with the blade, so as to clamp the latter firmly and remain permanently in contact therewith. That part of the bolster which is pressed inward is locked upon the upper corners of the tang produced by the expansion of its thickness, and the bolster is thus permanently secured upon the blade, while it is fitted closely

to the latter, as if formed in one piece therewith.

The notch or recess *d* is shown in Figs. 1, 5, and 6 of concave form, adapted to receive the 5 butt of the blade and brace it sidewise, while the front and rear edges of the bolster (shown at *l l* in Figs. 6 and 8) are free from any indentation through which the knife-blade itself would be exposed when finished. The bolster 10 thus presents much more strikingly the appearance of being integral with the blade than if the front and rear edges of the bolster exhibited notches into which the blade was inserted.

15 My invention is especially adapted to the manufacture of knife-blades from a species of white metal which takes a high temper by mere hammering, and by forming the bolsters by casting of the same metal and drilling the 20 hole *e* and milling out the notch *d*, I form a clean metallic contact between the bolster and blade, and form an article which appears as if made integral throughout. The thickening of the tang by compression upon its edges also 25 gives it a rigidity and magnitude adapted to cement it in a bone or composition handle, like a solid forged tang.

The notch *d* and hole *e* may be formed by casting or any other suitable means; but the 30 re-enforcing of the tang to stiffen and thicken it can only be produced by compression upon its edges, as it is designed in my invention that the tang shall be formed of sheet metal in one piece with the blade itself.

35 It is obvious that my improvements in the tang may be used independently of the improvements in the bolster, and I have therefore claimed the same apart from one another in the following manner.

40 Having thus set forth my invention, what I claim herein is—

1. The improved method herein described

for manufacturing the tang integrally with the blade of a sheet-metal knife, consisting in forming the tang in one piece of sheet metal 45 with the blade and wider than the proposed tang and compressing the tang upon its edges to thicken and narrow it, substantially as set forth.

2. The improved method herein described 50 for manufacturing the tang integrally with the blade of a sheet-metal knife, consisting in forming the tang in one piece of sheet metal with the blade and wider than the proposed tang and compressing the tang upon its edges 55 to narrow it and shape it into a cylindrical form thicker than the knife-blade, substantially as set forth.

3. The method herein shown and described 60 for applying a bolster tightly to a knife-blade having a tang thicker than the blade, which consists in, first, forming the bolster with a notch to fit the butt of the blade and a central aperture to admit the tang; in, secondly, slipping the tang over the bolster against the 65 butt of the blade, and in, thirdly, compressing the sides of the bolster to close the central aperture against the butt of the blade, as and for the purpose set forth.

4. A knife-blade formed of sheet metal with 70 tang thickened by compression upon its edges, substantially as set forth.

5. A knife-bolster having a notch formed in its top to fit the butt of a knife-blade and a hole of greater diameter than the breadth of the 75 notch formed through the bolster to admit the tang, as and for the purpose set forth.

In testimony whereof I have hereunto set my hand in the presence of two subscribing witnesses.

GEORGE HAVELL.

Witnesses:

A. G. WILLIAMS,
THOS. S. CRANE.

Corrections in Letters Patent No. 373,527.

- It is hereby certified that in Letters Patent No. 373,527, granted November 22, 1887, upon the application of George Havell, of Newark, New Jersey, for an improvement in the "Manufacture of Knife Blades and Bolsters," errors appear in the printed specification requiring correction as follows: On page 1, line 27, the compound word "button-shank," should read *butt or shank*, and on page 2, line 65, the clause "slipping the tang over the bolster" should read *slipping the bolster over the tang*; and that the Letters Patent should be read with these corrections therein that the same may conform to the record of the case in the Patent Office.

Signed, countersigned, and sealed this 29th day of November, A. D. 1887.

[SEAL.]

D. L. HAWKINS,
Acting Secretary of the Interior.
